UNITED STATES PATENT OFFICE.

HUGH CHRISTIE, OF MELROSE, NEW YORK, ASSIGNOR TO THE BIGELOW CARPET COMPANY, OF CLINTON, MASSACHUSETTS.

DESIGN FOR CARPET.

SPECIFICATION forming part of Design No. 11,859, dated July 13, 1880.

Application filed February 19, 1880. Term of patent 3½ years.

To all whom it may concern:

Be it known that I, HUGH CHRISTIE, of Melrose, in the county and State of New York, have invented a new and original Design for Carpets, of which the following is a specification.

This invention relates to a new design for carpets, oil-cloths, and analogous fabrics; and it consists in the novel grouping and configuration of figures hereinafter more fully described, and pointed out in the claims.

The accompanying photograph illustrates my new design.

On the back ground of the carpet is a large group, A, composed of flowers and leaves above a fence, a, which fence is overrun with vines and small leaves and flowers b, and under the fence is a bunch, d, of flowers and leaves.

B is a group composed of flowers and leaves 20 and a rustic fence, e.

C is another group composed of flowers and leaves, a rustic fence, f, an ornamental fence, g, and a representation of a cottage, h.

D is another group composed of flowers and 25 leaves, rustic branches, and an ornamental fence, i, which connects the groups A, D.

E is a group composed of a bunch of flowers and leaves, parts of a rustic fence, i', rustic branches crossing each other, and ornamental fences j, k, which connect the said groups with groups C and D, respectively.

F is a representation of part of a rustic bridge, and G is the representation of part of a rustic fence.

Above group E is an ornamental fence, l, connecting a cottage, l', with the group E.

The border H of the carpet is composed of groups of flowers and leaves, rustic fences, and crossed branches, and ornamental fences and cottages similar to the corresponding figures 40 on the body of the carpet.

I claim—

1. The design for a carpet, consisting of the group A, composed of flowers and leaves, the fence a, and the overrunning vines b, substantially as shown.

2. The design for a carpet, consisting of the group B, composed of flowers and leaves and the rustic fence e, substantially as shown.

3. The design for a carpet, consisting of the group D, composed of the flowers and leaves, an ornamental fence, i, and rustic branches, substantially as shown.

4. The design for a carpet, consisting of the group C, composed of leaves and flowers, rustic fence f, and ornamental fence g, and cottage h, substantially as shown.

5. The design for a carpet, consisting of the group E, rustic fences i, and branches, and ornamental fences j, k, substantially as shown.

6. The design for a carpet, consisting of the groups A, B and fence G and the background of the carpet, substantially as shown.

7. The design for a carpet, consisting of the groups A and D, substantially as shown.

8. The design for a carpet, consisting of the groups C, D, and E, substantially as shown.

9. The design for a carpet, consisting of the group E and of the ornamental fence l and cottage l', substantially as shown.

10. The design for a carpet, consisting of the groups A, B, C, D, E, fence l, cottage l', bridge F, and fence G, and the background of the carpet, substantially as shown.

HUGH CHRISTIE.
